UNITED STATES PATENT OFFICE.

MIRABEAU N. LYNN, OF RISING SUN, ASSIGNOR TO THE AMERICAN ELECTRIC HEADLIGHT COMPANY, OF INDIANAPOLIS, INDIANA.

STEAM-ENGINE.

SPECIFICATION forming part of Letters Patent No. 313,005, dated February 24, 1885.

Application filed May 20, 1884. (No model.)

To all whom it may concern:

Be it known that I, MIRABEAU N. LYNN, of Rising Sun, in the county of Ohio and State of Indiana, have invented certain new and useful Improvements in Steam-Engines; and I do hereby declare that the following is a full, clear, and exact description of the same, reference being had to the accompanying drawings, forming a part of this specification, and to the figures and letters of reference marked thereon.

My present invention is designed as an improvement upon multiple-cylinder engines of the class illustrated in applications filed by me January 10, 1884, and April 10, 1884, (numbered, respectively, 117,018 and 127,383,) to which engine it is here shown as applied; and my invention consists, essentially, in the novel and improved construction of the frame or stationary portions of the engine, whereby the cost of construction and the weight of the machine are materially reduced, various of its parts rendered interchangeable, thus facilitating repair, and the whole frame so constructed and organized as to present a compact, neat, and ornamental engine of great speed and power compared with its size and weight, all as hereinafter more fully and in detail described, and pointed out in the claims.

In the accompanying drawings, Figure 1 is a side view, and Fig. 2 an end view, of the main frame or casting. Fig. 3 is a longitudinal, and Fig. 4 a transverse, section of the main frame or casting with the piston and valve-cylinders in position. Figs. 5 and 6 are detail views showing the steam-port. Figs. 7 and 8 illustrate the manner of supporting the shaft. Fig. 9 is a top view of the cylinder-head. Fig. 10 is a plan view of the plate or casting to receive the end of the valve-cylinder.

Similar letters of reference in the several figures indicate the same parts.

The main frame or casing A, preferably cast in one piece of some light and strong metal—such, for instance, as phosphor-bronze—is composed of the cylindrical or other suitable-shaped portion, *a*, to which the heads B B' are applied and fastened by bolts in the usual manner; the base-piece or support *a'*, provided with an opening for the reception of a tube,

b, for the escape of the water of condensation; the three openings *a*², which are screw-threaded for the reception of the cylinders C; the three openings *a*³, for the valve-cylinders D, and the bearing block *a*⁴, for the main shaft E.

The piston-cylinders C are, for the sake of lightness and economy, constructed of brass or other suitable tubing, screw-threaded at one end for attachment to the casing A. The cylinder-heads C screw into the ends of the cylinders C, and are provided with the sockets *c c*, to receive a spanner or other form of wrench for tightening or loosening them. As thus constructed and combined, the several cylinders are susceptible of being removed, interchanged, replaced, or repaired independently and expeditiously, any tubing of the requisite strength, diameter, and uniform bore being readily applied.

At or near the outer end of each cylinder is formed an opening or port, *c'*, and oversaid opening is fitted a casting, F, which is bolted or otherwise securely fastened to the side of the cylinder. The casting F is made hollow or recessed, as shown by the dotted lines in Figs. 5 and 6, and in the sectional view, Fig. 3, and it has the segmental base or flange conforming to the curve or contour of the cylinder. By the side of each cylinder C is located a valve-cylinder, D, also composed of a tube screwed to the cap-plate *d* at one end and passing through the casting F, into which it is threaded and secured by the nut *f*, suitable packing material being interposed, if found desirable. The cap-plate *d* is fastened to the seat *a*⁵, formed on the main casing by bolts passing through the flanges or ears *f'*.

The valve-cylinders D are each provided with a series of holes or openings, *d'*, at or near their outer extremities and within the casting F, for the passage of the steam to and from the cylinder C.

As the engine described is designed to run at a high speed, it is of great importance not only that the parts should be convenient of access, but that the friction of the running mechanism should be reduced to a minimum. With this end in view, I have mounted the main shaft in a roller-bearing, T. Upon the shaft are forged, shrunk, or otherwise suitably secured two flanges or collars, *t*, pro-

vided with radial notches or openings t' , in which are fitted the bearing-blocks t^2 . A series of rollers, t^3 , provided with journals t^4 , are placed between the collars t , and resting 5 with their journals in the bearings t^2 . The rollers t^3 are clear of the shaft, but make contact with the interior of the bearing S , located on top of the bearing-block a^4 .

When the journals of the rollers become 10 worn, they are set up and held to their place against the inner surface of the bearing S by the introduction of a key or thin piece of some suitable material under the blocks t^2 , and, if desired, springs or adjusting-screws may be 15 introduced under said blocks.

As thus constructed, the friction of the shaft in its bearing is distributed between the several rollers and their journals, and as the journal is located within the main casing it is subject to the lubricative action of the exhaust steam, water of condensation, and oil.

The many advantages secured by the above simple yet efficient and novel arrangement and combination of parts will be obvious to 25 any one skilled in the art. It will be observed, in the first place, that I dispense with much of the heavy casting usually employed in engines of this class, while at the same time preserving ample strength. The connections are such 30 as require no special skill either to set up, repair, or construct the engine, ready to receive the operating mechanism, and by dispensing with projecting bolts and nuts on the cylinders the latter can much more conveniently be 35 wiped off or polished and made attractive. Moreover, access can readily be had to almost any part of the working mechanism by simply removing the cylinder-heads, the valve-cylinders, or the castings F , a point of very considerable importance in engines of this class 40 where all the working parts are inclosed or contained within a casing.

Having thus described my invention, what I claim as new, and desire to secure by Letters 45 Patent, is—

1. In a steam-engine, and in combination

with the main frame or casing for the operating mechanism, the piston, and valve-cylinders removably secured to the main casing and communicating with the interior thereof, the said valve-cylinders being perforated and communicating, through an intermediate support with the piston-cylinders, substantially as and for the purpose described. 50

2. In a steam-engine, the main frame or casing for the operating mechanism, provided with screw-threaded openings, the piston-cylinders constructed of tubing and provided with screw-threaded extremities for attachment to the casing, and removable heads united 60 to the cylinders by screw-threaded connections, substantially as described.

3. In a steam-engine, and in combination with the main inclosing-casing and piston-cylinders applied thereto, the casting F , applied 65 to the piston-cylinders, and provided with the opening or port communicating with the interior of said cylinders, and the valve-cylinders removably attached to the casing and extending 70 into and through said casting F , substantially as described.

4. In a steam-engine, such as described, the valve-cylinder removably attached to the main casing and casting F , substantially as described. 75

5. In a steam-engine, such as described, the combination of the main casing A , cap-plate d , valve-cylinder D , casting F , and the piston-cylinder C , the said valve-cylinder being screwed into the cap-plate and casting, as and 80 for the purpose specified.

6. The herein-described main frame or casing A , for the reception of the operating mechanism of a steam-engine, provided with the removable cylinders C , having threaded heads C' , the valve-cylinders D , cap-plate d , and casting F , uniting the cylinders C and D , as and for the purpose set forth. 85
